UNITED STATES PATENT OFFICE.

HENRY M. SHORT, OF PENN YAN, NEW YORK, ASSIGNOR TO SHORT ELECTRICAL MFG. CORP., OF PENN YAN, NEW YORK, A CORPORATION OF NEW YORK.

ELECTRIC CONDUIT AND PROCESS OF MAKING THE SAME.

1,396,789.

Specification of Letters Patent.

Patented Nov. 15, 1921.

Application filed February 24, 1920. Serial No. 360,565.

To all whom it may concern:

Be it known that I, HENRY M. SHORT, a citizen of the United States of America, residing at Penn Yan, New York, have invented a new and useful Electric Conduit and Process of Making the Same, of which the following is a specification.

My invention relates particularly to a flexible non-metallic type of construction for electric conduits.

The main object is the manufacture of a strong durable waterproof and fireproof construction which can be made economically and which can be readily finished.

15 The invention relates not only to the finished product, but to the method of making it.

The finished conduit in its preferred form embodies a continuous lining strip, a reinforcing helix adhering thereto, and an outer 20 textile fabric covering. The lining is preferably made of a strip of cloth such as a light cambric or heavy muslin gummed on one side. The helix is preferably formed of a twisted paper cord. The covering is 25 preferably of cotton knitted tightly. When the parts are assembled, the whole is immersed in a suitable compound to stiffen it and render it waterproof and substantially fireproof or slow burning.

30 Figure 1 is a diagrammatic view illustrating the different steps of forming the conduit.

Fig. 2 is a fragmentary view showing the parts of the finished conduit.

35 Fig. 3 is a fragmentary longitudinal sectional view on an enlarged scale.

Fig. 4 is a transverse sectional view on an enlarged scale.

The lining 5 is preferably gummed on the 40 outside and formed into a tube over the mandrel 6 preferably with the edges slightly overlapping. The cloth lining strip should have sufficient gum or other substance to make it somewhat stiff so that it will hold 45 its shape on the mandrel in the process of manufacture.

The cord 7 is wound tightly around the lining while it is on the mandrel. The cord is preferably damp or wet so as to cause it 50 to stick or adhere to the gummed surface of the lining and also so as to stiffen the cord somewhat. It will be obvious that instead of moistening the cord the gummed surface of the lining could be moistened first and 55 the cord wound on in its dry state. This

cord may be of any suitable cross sectional shape preferably round.

The outer covering 8 may be formed in any well known manner but is preferably knitted around the cord and the lay of the 60 cord and the knitting are made to correspond so that the loops 8' will draw part way down between the adjacent helices of the cord as indicated in Fig. 3.

After the covering has been formed the 65 conduit is carried through or immersed in a tank or tanks such as 9 containing the desired compound or compounds. This compound 10 soaks through the interstices of the covering and between the coils of the cord 70 when they are spaced apart so as to render the finished article substantially waterproof and fireproof and to stiffen it when cold and hold the parts permanently in their proper relation. Compounds for rendering a 75 conduit substantially waterproof and fireproof are well known in the art and need not be specifically described here.

By this construction, although the lining 80 adheres tenaciously to the cord, the conduit is nevertheless sufficiently flexible to pass the required tests. Ordinarily the use of damp or moist cord is sufficient to produce the necessary adherence. The underlying edge of the lining at the overlap may, however, 85 be dampened before forming, if desired, so as to more effectively unite the edges and prevent any possibility of the impregnating compound passing through to the interior of the conduit.

Obviously the interior of the tube may be 90 powdered with soap-stone or other anti-friction material if desired, and it will lodge in the interstices of the lining. Obviously the exterior of the product may also be treated 95 with material such as powdered mica as is customary in this art.

I claim:

1. The process of forming an article of the character described which comprises forming a lining strip having a gummed surface into a tube with the gummed surface on the outside, then winding a cord about the tube and moistening one of said elements so as to cause the cord to adhere to the 105 lining, then forming a covering about the cord and afterward immersing the parts in a suitable compound and permitting the compound to pass through the covering and between the coils of the cord. 110

2. The process of forming an article of the character described which comprises forming a gummed strip of cloth into a tube with the gummed surface on the outside, winding a moist cord on said tube and causing it to adhere thereto, and then forming a fabric covering around said cord. 40
3. The process of forming an article of the character described which comprises 45 forming a strip into a tube, winding a cord around said tube with its coils spaced apart and then knitting a covering about said cord, the pitch of the loops of said covering corresponding to the pitch of the helix of said cord so that the loops will lie between the adjacent helices of the cord.
4. A flexible non-metallic conduit comprising a longitudinally extending lining strip, a cord helically wound thereon and 50 with adjacent helices spaced apart from each other, and an outer textile covering knitted about said cord with the loops thereof fitting between adjacent helices of said cord.
5. The process of forming a flexible non-metallic conduit which comprises forming an inner smooth fabric lining, winding thereon a cord and simultaneously therewith causing said cord to adhere to the outer 55 surface of said lining and then forming a knitted fabric covering around said cord and then immersing said tube in a suitable impregnating compound.
6. A flexible non-metallic conduit comprising a longitudinally extending lining strip of stiffened cloth, a cord helically wound thereon and with adjacent helices spaced apart from each other, an outer textile covering knitted about said cord and 60
- lining and a waterproof and fireproof composition applied to said knitted covering and extending through the interstices of the covering and between the helices to the inner lining strip. 65
7. The process of forming a flexible non-metallic conduit which consists in forming on a mandrel an inner lining tube of a strip of stiffened cloth, then winding a cord tightly about said formed tube on the mandrel with adjacent coils spaced apart, then 70 knitting a covering tightly about said cord and lining tube on the mandrel, and afterward immersing the conduit parts in a suitable compound and permitting said compound to pass through the interstices of 75 said knitted covering and between the adjacent coils to the inner lining tube.
8. A flexible non-metallic conduit comprising a longitudinally extending lining strip formed into a tube, a cord helically wound thereon and having adjacent helices spaced apart from each other, and outer knitted textile covering inclosing said lining strip and helically wound cord and a waterproof and fireproof composition applied to said knitted textile covering and 80 extending through the interstices of said knitted covering and between the helices to the inner lining strip. 85
9. A flexible non-metallic conduit comprising an inner lining in the form of a tube, an outer covering in the form of a knitted tube surrounding said inner lining tube and a waterproof and fireproof composition applied to said outer knitted covering and passing through the interstices in 90 said covering. 95

HENRY M. SHORT.
